UNITED STATES PATENT OFFICE.

WILLIAM H. SIMONS, OF COLUMBUS, OHIO.

CAR-COUPING.

1,074,751.

Specification of Letters Patent.

Patented Oct. 7, 1913.

Application filed June 20, 1912. Serial No. 704,719.

To all whom it may concern:

Be it known that I, WILLIAM H. SIMONS, a citizen of the United States, residing at Columbus, in the county of Franklin and State of Ohio, have invented a certain new and useful Improvement in Car-Couplers, of which the following is a specification.

The chief object of this invention is to provide an improved car coupling of the 10 Janney type in which there is a vertically sliding locking block with means for setting the lock and opening the knuckle, both being operable by means of a sliding pin.

The invention is embodied in the example 15 shown in the accompanying drawings forming part hereof and particularly set forth in the following description, the features of novelty being pointed out in the appended claim.

20 In the said drawings—Figure 1 is a horizontal section on the line $x-x$ Fig. 2. Fig. 2 is a vertical section on the line $y-y$ Fig. 1. Fig. 3 is a perspective view of the lock. Fig. 4 is an elevation of the lock operating pin. Fig. 5 is an elevation of the inner end 25 of the knuckle. Fig. 6 is an elevation looking at the left hand side of the device as it appears in Fig. 2. Fig. 7 illustrates a modified form of the lock operating pin.

30 In the views 7 designates the draw bar, the head 7^a of which is of suitable form and provided with a suitable cavity to receive the operative parts.

8 designates the knuckle which is mounted 35 to swing horizontally on a vertical pin 19, as usual, in such couplings. The tail 8^a of the knuckle has its upper and lower sides inclined upwardly toward the side at which the knuckle is pivoted and so that upward 40 pressure against said lower side shall tend to throw the knuckle to open position.

The lock comprises a body or head portion 9 of oblong parallelepiped form, generally speaking, having a leg 9^a extending 45 downward from its lower side at one end. Said leg 9^a is beveled at 9^b to permit the tail of the knuckle to pass it when the latter is oscillated. The cavity of the draw head is constructed with a vertical recess 50 in which said lock can move vertically and be guided but permit the lock to slightly rock in a plane transverse the draw head.

10 is a wall in the lower portion of the cavity, the upper end of said wall affording 55 a shoulder upon which the leg 9^a rests to

support the lock in its elevated position, as shown by broken lines Fig. 2.

The lock operating pin 11, which is best illustrated in Fig. 4, consists of a body provided with a longitudinal opening 11^a 60 through which the lock projects. The pin at the lower end of this opening engages the lock to raise the same when the pin is raised. The pin works vertically in groove extensions 12 and 12^a of the recess for the lock 65 and is guided in its vertical movements thereby. The pin is arranged to engage the lock when raised at one side of the center of gravity of the lock so that the latter when supported by the pin tilts sufficiently 70 to throw the lower end of the leg over the shoulder of the wall 10. Hence in the preparation for uncoupling when the pin is released the leg engages and rests on the shoulder, as indicated by broken line Fig. 2. 75

Pivoted at 13 at the lower side of the draw head is an angular lever 14, the free extremity of which extends to a point in the cavity of the draw head under the tail piece of the knuckle. This lever 14 extends 80 through a slot 11^b of the pin 11. The lever 14 is operated by the pin 11 to throw the knuckle to open position, the pressure of the extremity of the lever on the inclined under side of the tail acting thereon to effect this 85 result, but the slot or opening 11^b is made sufficiently long to permit the lock to be raised to position to be supported on the wall 10 before raising the lever 14 to thus 90 actuate the knuckle. If the lever 14 be 95 raised to actuate the knuckle the lock is further raised but when the pin is released, the lock drops upon the tail of the knuckle and is supported thereby but tilted in the opposite direction. When the lock is supported on the wall 10 the knuckle is free to 100 turn outward to open position but when turned to full proper open position the high part of the tail of the knuckle engages the under side of the head of the lock and lifts it slightly so that it tilts in the opposite direction and fetches the lower end of the leg out of line with the shoulder of the wall 10 thereby permitting the lock to drop into knuckle locking position when the tail is 105 turned inward to the position it occupies when the knuckle is closed, as seen in Figs. 1 and 2. The operation therefore is briefly this: When it is desired to uncouple coupled cars equipped with such a coupling the 110

lock is raised by raising the pin until the lock is supported by the shoulder of the wall 10. The pin is then released and the cars can be separated. In separating the cars the knuckle is pulled to open position and in this operation the tail unseats the lock and supports it until the coupling is again coupled with another. Should it happen that the knuckle has not been in the uncoupling operation drawn to full open position, that position can be obtained by raising the pin 11 until the lever 14 actuates the knuckle and moves it to the proper position.

15 The pin 11 is shown as extending at its upper end through a hole in the top of the draw head, and provided with an eye for the attachment of an actuating device, but said hole in the draw head can be closed 20 and the pin can be shortened and formed at its upper end as shown in Fig. 7. The pin in either form can be raised by means of a bent lever 15 fulcrumed in ears 15^b at the under side of the draw head and provided 25 with an eye 15^a to which is connected a rod (not shown) extending to the side of the car, as usual, so as to be accessible without the necessity of going between the cars.

To prevent the dropping out of the knuckle pin 19 should it become broken I provide a headed pin 16 held in position under the lower end of said pin 19. Said pin 16 is passed through holes in an ear 17 on the draw head and in the ears 15^b and is secured from accidental removal by means of a cotter pin 18 inserted through the inner end of said pin 16 where it extends beyond

the ears 15^b. It will therefore be understood that should the knuckle pin become broken its parts are retained in position for service until a new one can be supplied.

What I claim is:

In a car coupling the combination with a draw head having a wall 10 forming a shoulder and a knuckle pivoted in the draw head having a tail piece inclined to the horizontal on its upper and lower sides, of a vertically moving and laterally swinging locking block for the tail piece consisting of the block 9 provided with a leg 9^a extending downward from its lower side at one end and an independent sliding lifter pin 11 in said draw head adapted to engage the other end of said block 9, said leg 9^a adapted when the block is sufficiently raised 50 by partially raising the lifter pin to swing laterally into engagement with said shoulered wall 10 to set the same and be released from said shoulder wall by swinging in the opposite direction when the block is 55 engaged by the inclined upper side of the tail of the knuckle when the latter is swung to open position, and a bent lever 14 independent of the lock to act on the lower inclined side of the tail piece, said lever being 60 actuated by said sliding pin to move the knuckle toward open position when said lifter pin is raised beyond the point to set the lock.

WILLIAM H. SIMONS.
